UNITED STATES PATENT OFFICE.

WILLARD P. PARSONS, OF FLUSHING, NEW YORK.

METHOD OF MANUFACTURING COAL-GAS AND COKE.

1,092,950.

Specification of Letters Patent. Patented Apr. 14, 1914.

Application filed November 14, 1908. Serial No. 462,559.

To all whom it may concern:

Be it known that I, WILLARD P. PARSONS, a citizen of the United States, residing in the city of Flushing, county of Queens, and 5 State of New York, have invented a certain new and useful Improvement in Methods of Manufacturing Coal-Gas and Coke, of which the following is a specification.

My invention relates to the manufacture 10 of coal gas and coke, and the object of my invention is to produce a maximum yield of gas and at the same time produce coke of the best quality.

In ordinary coal gas practice the maximum yield of gas may be obtained, but the coke is of an inferior quality, being soft and spongy, while in ordinary by-product coke oven practice the coke is of a good quality but only a part of the total yield of gas 20 is obtained as a by-product. By the use of my invention I am able to obtain a yield of gas equal to that of the best coal gas practice and a yield of coke equal to that of the best coke oven practice. I accomplish these 25 results by the use of the method of manufacture herein described in connection with the apparatus which is shown in the preferred form in the accompanying drawings.

Referring to the drawings, which illustrate a plant having two chambers heated from a common grate, Figure 1 is a vertical section through one of the distilling chambers. Fig. 2 is a partial vertical section through one of the walls adjacent to each 35 distilling chamber. Fig. 3 is a horizontal section through the line *a*—*b* of Figs. 1 and 2, showing the line *c*—*d* on which the section of Fig. 2 is taken. Fig. 4 is a rear view of the lower part of the plant showing 40 the furnace. Fig. 5 is a front elevation showing one chamber open and the other with its door closed.

A is a distilling chamber having its top and bottom inclined. It is charged with 45 coal through the opening *B* at the top, which is then sealed. At the bottom of the inclined chamber is a swinging door *C* through which the resultant coke is withdrawn. Near the top of the chamber is an outlet *D* 50 through which the gas is withdrawn to the common pipe *D'*.

Beneath both chambers is a common furnace *E* of any well known type for burning coal or other fuel, and from this source the 55 heat is so distributed as to uniformly heat

all parts of the chamber. To distribute the heat from the furnace I make the side walls of each chamber hollow, and arrange therein a main flue *F* which has the same inclination as that of the chamber, and lead from said main flue a series of vertical flues *G*, as will be seen in Fig. 2 and in dotted lines in Fig. 1. The vertical flues *G* open into a top flue *H*, which communicates with the discharge flue *I* leading to the stack or any 60 desired point where the excess heat may be used. Furthermore, as a continuation of the incline of the main flue *F*, I arrange a depending apron at the rear of the furnace beneath which the entire heat must pass 65 from the furnace to the main flue.

The operation of my invention is as follows: The distilling chamber is charged with coal so that it is almost entirely filled, and the charging opening is then sealed. 75 The heat from the furnace in passing through the inclined flues and the vertical flues connected therewith, is evenly distributed throughout all portions of the pile of coal. This heat is continued until all of the gas is distilled out of the coal and collected through the outlet *D* and the main pipe *D'*. When all of the gas has been distilled out of the coal, the coke is discharged 80 by opening the door *C*. This operation consumes several hours. By this method of manufacture I obtain all of the gas from the coal, and I obtain a better grade of coke than is usually obtained from the manufacture of coal gas, because of the fact that at 85 the time the gas is leaving the coal and the coal is being converted into coke. The condition of the mass is such that the internal pressure due to weight is distributed more evenly throughout the mass than under present practice, either in gas retorts or coke ovens. This distribution is due to the fact that there is a substantial pressure accumulated in the mass in more than one direction. 90

It will be obvious to those skilled in the art that my method of manufacture may be carried on in other forms of apparatus from that which I have shown herein, and I do not wish to be understood as limiting myself to any particular form of apparatus. 105

Having described my invention, what I claim is:

The method of manufacturing coal gas and coke which consists in completely filling 110

a relatively long and high air tight chamber with a mass of coal, supporting the mass at an angle slightly greater than the angle of rest of the mass during distillation so that there will be a substantial and nearly uniform pressure due to gravity throughout all parts of the mass, subjecting the mass to a uniformly distributed external heat,

drawing off the coal gas during distillation and collecting the resultant products.

In witness whereof I have hereunto set my hand, this 11th day of November, 1908.

WILLARD P. PARSONS.
